to Harry J. Neuman, Chicago, Ill.

Application April 25, 1949, Serial No. 2,244

Term of patent 3½ years

(Cl. D85—2)

To all whom it may concern:

Be it known that I, Le Roy Craven, citizen of the United States, residing at Chicago, in the county of Cook and the State of Illinois, at 911 Dakin Street, have invented a new, original, and ornamental Design for a Combination Cigarette Box and Ash Tray, of which the following is a specification, reference being had to the accompanying drawings, forming a part thereof.

In the drawings:

Fig. 1 is a front perspective view of a combination cigarette box and ash tray, showing my new design;

Fig. 2 is a front perspective view of the ash tray portion; and

Fig. 3 is a similar perspective view of the base portion showing the receptacle in which cigarettes may be placed.

I claim:

The ornamental design for a combination cigarette box and ash tray, as shown.

LE ROY CRAVEN.
